UNITED STATES PATENT OFFICE.

PATRICK GRAHAM, OF STOCKHOLM, SWEDEN.

MILLSTONE-SHARPENER.

SPECIFICATION forming part of Letters Patent No. 241,351, dated May 10, 1881.

Application filed January 26, 1881. (No model.) Patented in Sweden December 24, 1880.

To all whom it may concern:

Be it known that I, PATRICK GRAHAM, of Stockholm, in the Kingdom of Sweden, have invented a new and useful Improvement in 5 Millstone-Sharpener, of which the following is a specification.

Figure 1 is a plan view of the improvement. Fig. 2 is a sectional side elevation taken through the line x x , Fig. 1. Fig. 3 is a sectional side 10 elevation of the improvement, illustrating its use.

Similar letters of reference indicate corresponding parts.

The object of this invention is to break, 15 sharpen, or dress the grinding-surfaces of millstones in an expeditious and uniform manner.

The invention consists in constructing a millstone-sharpener of one or more toothed disks mounted upon or forming part of a radial arm 20 connected with the driving-spindle, its casing, or the eye of the stone, to adapt the sharpener to break or sharpen the grinding-surface of a millstone by being moved over the said surface under pressure, as will be hereinafter fully 25 described.

In the accompanying drawings, A is a ring of such a size as to fit upon the driving-spindle of the millstones, its casing, or rotate in the eye of the stone.

To the ring A are attached one or more radial arms, B, upon which are placed or made toothed disks C. The teeth of the disks C can 30 be varied, and the said disks can be made wider or narrower, and can rotate upon or with

or slide upon or with the arms B, as the character of the stone may require. 35

The sharpener A B C can be placed between two stones, as shown in Fig. 3, and made to operate by the movement of the runner, or the said sharpener can be used upon a single stone 40 by pressing it down upon the face of the stone by a weight or other suitable means.

The disks C can be arranged to sharpen the entire surface of the stone or stones at one operation, or gradually, by giving a reciprocating motion to the cutting-dies, or at two or 45 more operations, as may be desired.

With this construction the sharpener can be applied to horizontal and vertical stones with equal facility. Fig. 3 represents the sharpener 50 as applied to a set of vertical stones.

Having thus described my invention, I claim as new and desire to secure by Letters Patent—

1. A millstone-sharpener constructed substantially as herein shown and described, consisting of one or more radial arms, B, and one or more toothed disks, C, as set forth. 55

2. In a millstone-sharpener, the combination, with the ring A, of the radial arm B and one or more toothed disks, C, substantially as 60 herein shown and described, whereby the grinding-surface of a millstone can be broken or sharpened, as set forth.

PATRICK GRAHAM.
